CLAIM

The ornamental design for a one-handed, forearm-braced paddle handle, as shown and described.

DESCRIPTION

FIG. 1 is a perspective view of a one-handed, forearm-braced paddle handle showing our new design;

FIG. 2 is a perspective view comparable to FIG. 1 except on enlarged scale;

FIG. 3 is a perspective view comparable to FIG. 2 except from a vantage point on about a 180° orbit relative to FIG. 2 but in about the same overhead plane;

FIG. 4 is a side elevational view of FIG. 3, the opposite side being a mirror opposite;

FIG. 5 is a top plan view thereof;

FIG. 6 is a bottom plan view thereof;

FIG. 7 is front elevational view thereof; and,

FIG. 8 is a rear elevational view thereof.

The broken lines in the drawing represent environmental subject matter that forms no part of the claimed design.
